UNITED STATES PATENT OFFICE

100,950

DESIGN FOR A SPOON OR SIMILAR ARTICLE

Charles A. Joslin, North Attleboro, Mass., assignor to R. Blackinton & Co., North Attleboro, Mass., a copartnership

Application June 22, 1936, Serial No. 63,431

Term of patent 14 years

To all whom it may concern:

Be it known that I, Charles A. Joslin, a citizen of the United States, residing at North Attleboro, in the county of Bristol and State of Massachusetts, have invented a new, original, and ornamental Design for a Spoon or Similar Article, of which the following is a specification, reference being had to the accompanying drawing, forming part thereof:

In the drawing

Fig. 1 is a plan or topside view of a spoon embodying the design.

Fig. 2 is a bottom plan view illustrating the appearance of the back of the spoon.

Fig. 3 is a cross sectional view on line 3—3 of Fig. 2 showing the transverse contour.

What I claim is:

The ornamental design for a spoon or similar article substantially as shown.

CHARLES A. JOSLIN.
